UNITED STATES PATENT OFFICE

2,394,103

ELECTROMAGNET

Louis T. Rader, Schenectady, N. Y., assignor to
 General Electric Company, a corporation of
 New York

Application October 20, 1942, Serial No. 462,662

4 Claims. (Cl. 175—338)

The invention relates to electromagnets, and the principal object is to provide an improved form of alternating current electromagnet of the cast magnetic shell enclosed solenoid type having a separately sealed off movable laminated plunger cooperating with a magnetic out-of-phase flux producing sealing member to provide a quiet and strong enough pull for operating valves or other relatively heavy loads.

Usually a cast magnetic shell type of solenoid has required energization with direct current in order to obtain a quiet and strong pull on the plunger as well as to prevent overheating. Upon alternating current energization of such an electromagnet, the plunger may tend to chatter when in closed position so as to create excessive noise under even a very light load. Likewise, the usual fluid-tight sealing tube for the plunger that extends from the body of the valve or other operated device inside the operating solenoid may be subject to excessive heating losses due to the eddy currents induced therein when the solenoid is energized with alternating current. Also, excessive heating losses due to hysteresis and eddy currents in the usual cast magnetic enclosing shell of the solenoid may result in case of alternating current energization thereof. Consequently, the temperature to which the usual direct current cast magnetic shell enclosed solenoid is subjected, in case of alternating current energization thereof, ordinarily may exceed safe operating limits. Furthermore, the demagnetizing action of the eddy current and hysteresis losses may become so great that very little, if any, effective magnetic pull is available for operating the plunger.

One of the specific objects of the present invention is to provide an improved form of longitudinally laminated pole and plunger structure with interposed solid magnetic out-of-phase flux producing plate intimately interlinking the opposite longitudinal laminations of the pole and plunger through a short magnetic path extending transverse a wide and flat eddy current conductive path for reducing the magnetic losses and thereby increasing the effective quiet magnetic pull on the plunger of an alternating current solenoid.

Another specific object is to provide an improved form of plunger sealing and guiding tube structure having relatively low eddy current losses in producing out-of-phase flux for holding the plunger firmly in attracted position during alternation of the current in an alternating current solenoid.

A more specific object is to provide the plunger guiding and sealing tube with an improved form of magnetic pole shader disc for sealing the end thereof inside the solenoid as well as providing

a sufficiently strong out-of-phase flux for maintaining the plunger quiet in the attracted position even under relatively heavy load when the solenoid is energized with alternating current.

5 Further objects and advantages of the improvements of the present invention will become apparent from the following description of the accompanying drawing, in which the single figure is a sectional view of an alternating current 10 solenoid of the enclosed cast magnetic shell type having a separately sealed off movable plunger for operating a valve and embodying the invention in a preferred form.

As shown in the drawing, the solenoid magnet 15 winding 10 is of suitably insulated annular form and is provided with the terminal leads 11 for energizing the solenoid from an alternating current source, such as an ordinary 60-cycle commercial supply line. The solenoid 10 is totally 20 enclosed within a separable flux conducting cast iron shell indicated generally by the character 12 and comprising the top wall 13, the bottom wall 14 and the cylindrical side wall 15. Preferably, the top wall 13 and the cylindrical side wall 25 15 are cast integrally of soft cast iron and provided with a series of radial heat radiating fins 16 for dissipating the heat produced by eddy currents and hysteresis in the shell. Also, preferably a wiring connection box 17 is formed to 30 project from one side of the enclosing shell wall 15 and provided with a threaded opening 18 for receiving the conduit pipe 19 carrying the alternating current supply lines so that the whole device becomes splashproof, waterproof, and even 35 explosionproof. A removable sealing cover 20 provides the necessary access for connecting the solenoid terminal leads 11 with the supply lines.

The bottom wall 14 of the enclosing shell 12 preferably is cast as an integral part of the enclosing sleeve 23 for the movable valve or other load device that is to be operated by the solenoid. As shown, the valve enclosing sleeve 23 is removably secured to the main body of valve 24 by the bolts 25 with a portion of the sleeve 23 cut away 45 to show the pivot yoke 26 that is carried by the pivot pin 27 extending through the laminated magnet plunger 28, and connected to the valve operating stem 29 that is to be operated upon energization of the solenoid 10. The separable 50 parts of the solenoid enclosing shell 12 are held in fluid-tight engagement by the screws 30 and the solenoid winding 10 is held in firm engagement with the bottom wall 14 by the spring washer 31.

55 Since the particular structure of the valve 24 is not of the essence of the present invention, the details thereof are not shown. However, for low pressure work, the operating stem 29 may be connected to operate the main valve parts directly, 60 while for high pressure work, the operating stem

28 may be connected to a small pilot valve that controls the pressure operation of the main valve, if desired.

To conform with the present invention, the magnet plunger 28 is formed of laminated magnetic material, as shown, preferably silicon steel, and is sealed off fluid-tight from the other parts of the operating solenoid by the cylindrical sealing and guiding tube 33. To reduce the eddy currents induced therein, this tube 33 is formed of relatively thin high resistance non-magnetic material, such as stainless steel or Nichrome, and preferably is provided with a conically flared end 33a so that it can be tightly clamped in fluid-tight engagement with the sloping shoulder 34 extending from the cylindrical wall of the opening 35 in the bottom shell wall 14 through which the plunger 28 operates. The conically flaring end 33a of the tube 33 is clamped in position by the extra elongated annular clamping nut 36 of soft steel which preferably closely surrounds the laminated plunger 28 so as to provide a magnetic flux path of low reluctance from the bottom shell wall 14 to the plunger 28 with a minimum air gap therein. However, the annular clamping nut 36 preferably is of just slightly larger internal diameter than the internal diameter of the sealing and guiding tube 33 so that the plunger guiding tube will always prevent actual engagement of the plunger 28 with the clamping nut 36.

In accordance with the present invention, the end of the plunger sealing and guiding tube 33 that extends inside the solenoid 10 is sealed by a relatively thin out-of-phase flux producing and conducting plate or disc 39 of solid magnetic material. This out-of-phase flux producing and conducting plate or disc 39 preferably is formed of silicon steel so as to avoid the work hardening or aging characteristic of soft steel which may build up its residual so that it tends to become permanently magnetized and thus may tend to hold the plunger in its attracted position even though the solenoid 10 is deenergized. Preferably, the plate or disc 39 is provided with a peripheral shoulder 39a that engages with a complementary inwardly projecting shoulder 33b formed at the top of the sealing and guiding tube 33. Since the cylindrical side walls of the sealing and guiding tube 33 are relatively thin, preferably being only about .030" thick, this interlocking shoulder construction insures that the solid plate or disc 39 of magnetic material is securely anchored in the end of the tube so as to withstand the very high internal pressures to which the sealing tube and disc may be subjected in case the valve 24 is employed for controlling high pressure fluids. The plate or disc 39 may be pressed into position, as shown, at the inside end of the tube 33 and thereby provide a fluid-tight joint. However, if desired, the plate or disc 39 may be further secured to the end of the tube 33 by suitable brazing or welding.

In order to minimize the eddy current losses in the sealing tube 33, this tube preferably is formed of a high resistance non-magnetic material, such as stainless steel or Nichrome, as previously noted. Also, the length of the tube 33 extending inside the solenoid 10 is reduced to the bare minimum that will provide a sufficiently long stroke for the plunger 28 to effectively operate the valve. Thus by forming the tube 33 of high resistance non-magnetic material, as well as by minimizing the thickness and

the length thereof, the heat loss produced by the eddy currents within the tube upon alternating current energization of the solenoid 10 can be reduced to a minimum. Moreover, since the inside of tube 33 is in direct contact with the fluid controlled by the valve 24, the heat generated in the tube 33 will be transmitted directly to and carried away by the fluid except, of course, when the fluid may have a higher temperature as, for example, high pressure steam.

A pole 40 of laminated magnetic material, preferably silicon steel, is adjustably mounted in flux conducting relation in the recess 41 formed in the top wall 13 of the cast iron shell 12 opposite the central opening 35 in the bottom wall 14 through which the plunger 28 operates upon energization of the solenoid. The laminated pole 40 is clamped in intimate magnetic contact with plate or disc 39 by means of the enlarged stop screw 42 which is threaded centrally in the top wall 13 of the cast iron shell 12. This enlarged stop screw 42 not only facilitates the flux conduction between the pole 40 and shell 12 but also enables the pole 40 to be forced into firm engagement with the relatively thin out-of-phase flux producing and conducting plate or disc 39 so as to receive the impact of the plunger 28 when the plunger moves to the attracted position. Also, in this way, when the solenoid 10 is energized from the alternating current source, the relatively thin solid magnetic out-of-phase flux producing and conducting plate or disc 39 is interposed between the laminated plunger 28 and the laminated pole 40 in intimate flux conducting contact with each so as to provide a sufficiently strong out-of-phase flux for maintaining the plunger in firm and quiet engagement with plate or disc 39 during alternation of the solenoid energizing current under even heavy loads.

The out-of-phase flux producing action of the thin solid plate or disc 39 of magnetic material may be understood by considering the plate or disc 39 as a continuous series of concentric rings of solid conductive metal within each of which eddy currents are produced by inductive action upon movement of plunger 28 to the attracted position due to energization of the alternating current solenoid 10. Under these operating conditions the eddy currents inductively produced in each of the assumed concentric rings serve to provide an out-of-phase flux when the energizing alternating current of the solenoid 10 passes through the zero value. Since the assumed rings are concentric, the out-of-phase flux producing action thereof becomes cumulative along their axis and thus results in a very strong centralized out-of-phase magnetic field. Due to the intimate magnetic engagement of both the laminated plunger and the laminated pole with the opposite sides of the solid thin plate or disc 39 of magnetic material, the out-of-phase flux produced by the eddy currents in the disc is most effective in holding the plunger firmly and quietly in the attracted position during alternation of the solenoid energizing current since there is practically no air gap in the symmetrical local magnetic circuit between the pole 40 and plunger 28. In this local magnetic circuit the thin magnetic disc 39 is disposed between and normal to the opposite longitudinal laminations of the pole 40 and plunger 28 so as to interlink these longitudinal laminations through a short magnetic path extending transverse the wide and flat conductive path for concentric eddy current flow in

the disc. Thus the plate or disc 39 serves to provide a very strong and effective out-of-phase flux for holding the plunger in the attracted position since the solid plate or disc 39 is relatively thin. In fact, it has been found that increasing the thickness of the disc 39 to much more than one-eighth of an inch merely increases the heat loss due to the increased eddy currents produced therein but does not materially increase the out-of-phase flux effective for holding the plunger in the attracted position. This one-eighth inch effective thickness limitation for the solid steel disc 39 corresponds substantially to twice the usual effective alternating flux penetration depth permitted by the so-called skin effect of any relatively thick solid steel body at the ordinary sixty-cycle commercial frequency. Hence, in case the thickness of disc 39 should be increased materially beyond this limitation, the resulting skin effect of the disc will tend to render the out-of-phase plunger holding action produced by a thin disc ineffective.

Since the plunger 28 and the pole 40 both are of laminated magnetic material, the heat loss produced by eddy currents and hysteresis there-in during operation of the solenoid is practically negligible. An analysis of the total heat loss of a particular solenoid constructed as illustrated in the drawing shows that when energized with alternating current at the rated voltage, the total watts loss produced on continuous heat run in the solenoid and its magnetic circuit is 194. Of this the out-of-phase flux producing disc 39 generates only twenty-three watts, the sealing and guiding tube 33 twenty-six watts, the copper of the solenoid winding 10 four watts, and the remaining 141 watts are produced by hysteresis and eddy currents in the cast iron shell 12. Thus the heat radiating fins 16 are located so as to dissipate the relatively large heat loss generated directly in the cast iron shell 12, while the heat generated in the disc 39 and the tube 33 may be readily dissipated to the fluid. In this way, the operating temperature to which the solenoid 10 is subjected is maintained within permissive safe limits.

For best results, the solenoid 10 should be relatively short in length with the operating air gap between the plunger 28 and pole 40 located centrally within the solenoid as shown, preferably the overall height of the solenoid coil 10 being approximately three times the air gap through which the plunger 28 must operate. It has been found that making the solenoid any larger with the expectation of increasing the permissible watt input thereto and thereby increasing the pull exerted on the plunger 28 produces negligible results. The increase in watts due to the added height of the coil and its shell simply increases the losses therein without appreciably increasing the effective quiet pull on the plunger.

What I claim as new and desire to secure by Letters Patent of the United States is:

1. In combination, a solenoid having a cast iron enclosing shell provided with a plunger opening and a longitudinally laminated magnetic pole projecting from said shell inside said solenoid opposite said opening, a load operating longitudinally laminated magnetic plunger movable through said opening into opposing attracted relation with said pole upon energization of said solenoid with alternating current, a tube formed of a high resistance nonmagnetic metal and having sealing connections with said opening and extending inside said solenoid for guiding said

plunger, and a thin disc of magnetic flux and eddy current conductive metal in abutting engagement with said pole to receive the impact of said plunger upon attraction thereof and sealing the inner end of said tube and magnetically interlinking the opposite longitudinal laminations of said pole and plunger in said attracted relation through a short magnetic path extending transverse a wide and flat eddy current conductive path to produce an out-of-phase flux for holding said plunger attracted during alternation of the alternating energizing current of said solenoid.

2. In combination, an alternating current solenoid having a magnetic circuit including a longitudinally laminated pole extending inside said solenoid and an opposing longitudinally laminated plunger attracted toward said pole upon energization of said solenoid, and a plunger guide tube formed of a high resistance nonmagnetic material extending inside said solenoid around said plunger and having a thin disc of magnetic flux and eddy current conductive material extending across the end thereof in abutting engagement with said pole for receiving the impact of said plunger upon attraction thereof and for magnetically interlinking the opposite longitudinal laminations of both said pole and said plunger upon attraction thereof through a short magnetic path extending transverse a wide and flat eddy current conductive path to inductively produce out-of-phase flux for maintaining said plunger attracted upon alternation of the energizing current of said solenoid.

3. In combination, an alternating current solenoid having a laminated plunger and a magnetic circuit for conducting flux thereto including a laminated pole extending inside said solenoid, means providing a sealed enclosure for said plunger including a tube formed of a high resistance nonmagnetic metal extending inside said solenoid around said plunger and a thin plate of magnetic flux and eddy current conducting metal provided with peripheral connections for sealing said tube and supporting said plate in abutting engagement with said pole to receive the impact of said plunger upon attraction thereof, said plunger and pole each having the laminations thereof normal to and in contact with said plate upon attraction of said plunger to magnetically interlink said laminations through said plate to produce out-of-phase eddy currents in said plate for maintaining said plunger attracted upon alternation of the energizing current of said solenoid.

4. In combination, an alternating current solenoid having a longitudinally laminated plunger, a plunger guide tube formed of a high resistance nonmagnetic material extending inside said solenoid and having a thin plate of magnetic flux and eddy current conducting material mounted transverse said tube for abutting magnetic engagement with said plunger upon attraction thereof, a magnetic circuit for said solenoid including a shell having a longitudinally laminated pole and a magnetic stop member adjustable in said shell for clamping said pole in abutting magnetic engagement with said plate to produce out-of-phase flux for maintaining said plunger in engagement with said plate upon alternation of the energizing current of said solenoid and for receiving the impact of said plunger upon attraction thereof.

LOUIS T. RADER.
